MACHINE FOR MAKING ELONGATED TUFTS

Joseph K. McCutchen, Ellijay, Ga.

Application November 24, 1944, Serial No. 564,939

4 Claims. (Cl. 112—79)

1

This invention relates to a sewing machine and more especially to a sewing machine equipped with specially designed apparatus whereby elongated tufts can be formed on the lower side of a base fabric as the fabric is passed through the machine.

It is an object of this invention to provide a sewing machine having a plurality of needles for piercing a base fabric, and carrying along with each needle a strand, together with means for passing between the strand and the needle and above the eye of the needle after the needles have pierced the fabric for forming a loop on the lower side of the fabric and extending this loop to an elongated position together with other means for engaging the loop while held by the first looper and removing it from the first looper and further elongating the loop and transferring it onto a looper bill where it is held and severed while the first and second loopers are handling the formation and transfer of loops downwardly to be deposited onto the looper bills.

It is another object of this invention to provide a sewing machine having a plurality of vertically reciprocating needles carrying the strands of yarn through a base fabric together with a looper associated with each needle for passing between the needle and the yarn carried thereby and above the eye of the needle for engaging the yarn and forming a loop as the needle is withdrawn upwardly through the fabric and also elongating said loop, together with a second looper for engaging the loop held on the first looper when it is in extended position and removing this loop from the first looper and further elongating the loop and transferring it onto an oscillating looper bill which has associated therewith a cutter or knife, which when the elongated loop has been transferred onto the looper bill as the looper bill moves rearwardly, the knife will move upwardly to sever some, but not all, of the loops carried by the looper bill.

Some of the objects of the invention having been stated, other objects will appear as the description proceeds, and taken in connection with the accompanying drawings, in which—

Figure 1 is a front elevation of a sewing machine head equipped with my special apparatus and showing parts thereof in section;

Figure 2 is a vertical sectional view showing the

2

linkage connection between certain shafts and taken along a line 2—2 in Figure 1;

Figure 3 is a bottom plan view of Figure 1;

Figure 4 is a transverse sectional view taken substantially along a line 4—4 in Figure 1;

Figure 5 is a horizontal sectional view taken substantially along a line 5—5 in Figure 4;

Figure 6 is a view taken along the same line as Figure 4, but showing the parts in a different position.

Referring more specifically to the drawings, the numeral 10 indicates a conventional bed plate of a sewing machine having an uprising portion 11 and a horizontally disposed portion 12 provided with a conventional head 13 in which the needle bar 15 is mounted for vertical reciprocatory movement and also a presser bar 16 having a presser member 16a secured on its lower end and a presser foot 17 pivotally connected as at 18 to the lower end of the presser member 16, all of a conventional nature.

The lower end of the needle bar 15 has a transverse portion 20 in which a plurality of needles 21 are mounted, said needles having a conventional eye 22 near the lower end thereof. The head 13 has a plate 14 secured thereon on which tension devices 14a are mounted and through which the strands of yarn pass on their way to the needles. A plate 19 is also secured on the front of head 13 which has holes therethrough for also guiding the strands of yarn.

The horizontal portion 12 and the uppermost portion of portion 11 of the sewing machine goose-neck has rotatably mounted therein a drive shaft 23 which has a hand wheel 24 fixedly secured thereon and there is also fixed thereon a pulley 25 on which a suitable belt, not shown, is adapted to be mounted, said belt being suitably mounted on a motor shaft pulley, not shown, for driving the sewing machine.

The drive shaft 23 has an eccentric portion 27 thereon on which a conventional forked upper end 28 on a connecting rod 29 is mounted, said connecting rod 29 having pivotally secured thereto as at 30 a link 31 whose other end is pivotally secured to the free end of a link 33, the other end of which is pivotally mounted on a stud 34 extending from the interior of the upright portion 11. This gives the connecting rod 29 not only an up and down motion but also a lateral swinging

motion for proper operation of rear feed dog shaft 35 which is mounted for oscillation at its ends in suitable pivot screws such as 37. The rear feed dog shaft has adjustably secured thereon a lever 38, the free end of which is pivotally connected to the lower end of connecting rod 29, all of this being of conventional nature.

The main drive shaft 23 has also thereon, an eccentric portion 40 which is surrounded by the upper end portion 41 of a connecting rod 42, the lower end of which is pivotally connected to a lever 43 adjustably secured on the front feed dog shaft 44 mounted at its ends for oscillation on suitable pivot screws 45. This front feed dog shaft 44 has suitable levers 46 adjustably secured thereon, whose free ends have pins 47 which have sliding movement in open-ended slots 48 in feed dog frame 49, the rear end of the feed dog frame 49 being pivotally connected as at 50, to the upper ends of arms 51 extending from the rear feed dog shaft 35.

The feed dog frame 49 has upwardly projecting portions 52 of a conventional nature which work in suitable slots in a throat plate 53 secured on the upper side of the base plate 10. The feed dog portions 52 project through said slots to feed a fabric 55 rearwardly. The throat plate also has openings through which the needles 21 project downwardly, each needle carrying a strand of yarn 56 for the formation of loops on the lower side of the fabric.

The machine is also equipped with downwardly projecting lugs 60 and 61 to which are secured plates 62 and 63 for supporting some of the additional shafts which are presently to be described.

Immediately below the front feed dog shaft 44 there is disposed a looper shaft 65 which is mounted at its ends in suitable pivot screws 66 and 67 disposed in the plates 63 and 62, respectively. This first looper shaft 65 has adjustably secured thereon an arm member 68, the free end of which is pivotally connected with the lower end of a connecting rod 69 whose upper end portion 70 surrounds a suitable eccentric on the main drive shaft 23 for imparting oscillatory and vertical reciprocatory motion to the connecting rod 69 and oscillatory motion to the looper shaft 65.

The looper shaft 65 has adjustably mounted thereon a plurality of split blocks 72 which are secured in position by means of suitable screws 73. Each of these blocks has adjustably mounted thereon a looper finger 74 by means of screws 75 penetrating a slot 76 in the looper member 74 and being threadably embedded in the blocks 72. The free end of looper member 74 has a hook 77 thereon which is adapted to pass between the needle and the yarn carried thereby and above the eye of the needle when it is in lowermost position for engaging the yarn and forming a loop.

Disposed rearwardly and at some distance below the shaft 65 is a second looper shaft 80 which has an arm 81 adjustably secured thereon which is pivotally connected to the lower end of a connecting rod 83 whose upper end has a circular portion 84 surrounding an eccentric 64 on the shaft 23 which gives a vertical reciprocatory motion and a slight swinging motion to the connecting rod 83 which in turn gives oscillatory motion to the second looper shaft 80. Second looper shaft 80 is pivotally mounted at its ends for oscillation in suitable pivot screws 85. The second looper shaft 80 has adjustably se-

cured thereon a plurality of split blocks 86 which are confined in clamping relation on the shaft 80 by means of screws 87. Each block 86 has adjustably secured thereon a rod 79 by means of a set screw 88a and the upper and rear-most end of rod 79 has secured thereon by brazing or otherwise a looper member 88 which has a pointed bill portion 89 on its free end which is adapted to pass upwardly above the bill 77 and to remove the loop from the bill 77 and to extend it further downwardly as shown in Figure 4.

Also mounted in brackets 62 and 63 are pivot screws 90 and 91 which oscillatably support the ends of a looper bill shaft 92. This looper bill shaft has adjustably secured thereon an arm 93 to the free end of which is pivotally connected the lower end of connecting rod 94 which extends upwardly and has a circular portion 95 surrounding a suitable eccentric 95a disposed on the shaft 23 for imparting swinging and reciprocatory motion to the connecting rod 94 and oscillatory motion to the shaft 92.

The shaft 92 has adjustably mounted thereon a plurality of split blocks 96 which are confined on the shaft 92 by means of a screw 97. Each of these blocks 96 has suitably mounted therein a rod 98 by means of a set screw 99. The upper end of this rod, as will be observed in Figure 4, has a looper bill shank 100 brazed or welded thereon which has a looper bill 101 extending forwardly from its upper end and has a down-turned pointed portion 102 to prevent the loops from slipping off the looper bill 101. This looper bill 101 is adapted to penetrate between two sides of a loop when this loop is moved downwardly by further counter-clockwise motion of the shaft 80 in Figures 4 and 6. In other words the bills 89 on rods 87 move down far enough to where forward motion of the looper bill 101 will cause its down-turned pointed portion 102 to enter above the bills 89 on shaft 87 which will cause the loop to be transferred from hook portion 89 onto the looper bill 101.

Fixed to the lower side of the bed plate of the machine and projecting downwardly therefrom is a bracket 105 and a pivot screw 106 is fixed in this bracket and also a pivot screw 107 is threadably secured in bracket 62 and on these pivot screws is oscillatably mounted a square shaft 108 which has adjustably secured therein short rods 109 by means of a set screw 110. These rods have each a slot 111 therein in which the lower end of a cutter knife 112 slidably fits and said cutter knife being adapted to be confined in an adjusted position by means of a sleeve 114 slidably fitting on the rods 109 and being driven against the edge of the cutter blade 112 by means of a screw 113 threadably secured in the interiorly threaded outer end of each of the rods 109. The upper ends of the cutter blades are adapted to slidably engage the looper shank 100 and looper bill 101 due to the flexing of the blade by slightly turning the rods 109 before securing them in adjusted position so as to cause the upper cutting edge of the blade 112 to slidably engage the shank 100 and looper bill 101 in its upward and downward movement relative to the looper bill shank 100 and the looper bill 101 to cut the loops upon rearward upward movement of the looper bills.

The looper bill shaft 92 has an arm 115 adjustably mounted thereon by means of one end being split and having a clamping screw 116 slidably penetrating one portion and threadably secured in the other portion. The free end of this arm

has pivotally secured thereto a link 117, the other end of link 117 being pivotally secured to the free end of an arm 118, the other end of the arm 118 being adapted to fit around cutter shaft 108, and this split end of arm 118 has a screw 119 therein for causing the end of arm 118 to clampingly engage shaft 108.

It is to be noted that shafts 65, 80 and 92 are driven directly from the main drive shaft 23 and not from the feed shafts 35 or 44 or from a separate source of power. By having the eccentrics on the main shaft and the connecting rods 63, 69 and 96 driven thereby and connected to arms on the respective shafts 65, 80 and 92 a positive and trouble-free drive is provided.

Method of operation

As the needles move from uppermost to lowermost position, and just after the eyes of the needles have passed through the throat plate, the hooks 71 are up against the throat plate and the hooks 89 have moved downwardly just below the path to be traveled by the looper bill 101, and upon further downward movement of the needles, the loopers on the first looper shaft 65 start moving downwardly between the needle and the strand carried thereby above the eye of the needle to form the loops and the looper bills 101 being passed through the loops held by the loopers on the second looper shaft, then the loopers on the second looper shaft start moving reversely or upwardly and backwardly while the loopers on the first looper shaft move downwardly and by the time the loopers on the second looper shaft move above the points on the loopers on the first looper shaft the looper bills 101 start moving backwardly and the knives 112 start sliding upwardly on the looper bill shank to sever the loops and as the looper bill 100 moves backwardly, the hooks on the ends of the loopers on the second looper shaft move past the lowered tips of the loopers on the first looper shaft to remove the loops carried thereby while the preceding loop has been cut by the knives on the lowermost looper bills. In other words, it is seen that as a loop is being formed by the loopers on the first looper shaft the loopers on the second looper shaft are moving upwardly to receive the loops when transfer operation is ready, and at the same time, the loops which have already been transferred to the looper bills 101 are being cut while the loops are transferred from the first looper bills to the second loopers to be carried downwardly to be engaged by the looper bills 101 while another set of loops is beginning to be formed by the loopers on the first looper shaft.

In the drawings and specification, there has been set forth a preferred embodiment of the invention, and although specific terms are employed, they are used in a generic and descriptive sense only and not for purposes of limitation, the scope of the invention being defined in the claims.

I claim:

1. In a sewing machine having a vertically reciprocating needle for carrying a strand through a base fabric, an oscillating looper adapted to pass between the needle and the strand carried thereby for forming a loop and moving further downwardly to increase the length of the loop, a second oscillating looper member disposed below the first looper and adapted to pass into the loop and engage the same and hold the same while the first looper member moves upwardly and for-

wardly of the path traveled by the needle to a position ready to pass between the needle and a strand carried thereby as the needle again moves downwardly, the second looper member being adapted to move the loop further downwardly and to elongate the loop to a further degree than the elongation imparted by the first looper member, an oscillating looper member having a looper bill adapted to pass into the loop while it is held by the second looper member, and cutting means associated with the oscillating looper bill for cutting some but not all of the loops held on the looper bill during each oscillation of the looper bill member.

2. In a sewing machine having a plurality of vertically reciprocating needles disposed in side by side spaced relation to each other and each having an eye for carrying a strand through a base fabric, an oscillatable shaft disposed below and in front of the projected line of travel of the needle and having a plurality of looper arms thereon adapted to pass between the needles and the strands carried thereby for engaging the strands and forming loops as the needles move upwardly, and as the needle moves upwardly, the looper members being adapted to move further downwardly to greatly elongate the loops being formed upon upward travel of the needle, a second looper shaft disposed below the first looper shaft and having a plurality of looper members thereon, the second shaft being oscillatable whereby the second looper members will pass into and engage the loops and transfer the same from the first looper members and move further downwardly to elongate the loops to a greater degree than they were elongated by the first looper members, a third oscillatable shaft having a plurality of looper bill members thereon having looper bills on their upper ends and adapted to swing forwardly into the loops while they are held by the second looper members in their lowermost position and to engage and hold the loops while the second looper members move out of the loops to a position ready to receive the loops being moved downwardly by the first looper members, and cutting means associated with the looper bill members for cutting some but not all of the loops held on the looper bills of the looper bill members.

3. In a sewing machine having a plurality of vertically reciprocating needles adapted to pierce a base fabric and carry therewith a strand of yarn, a looper shaft having a plurality of arms thereon and having hooks on their outer ends, the hooks being adapted to pass between the needles and the strands carried thereby and to move the strands downwardly to form elongated loops while the needles move upwardly, a second looper shaft mounted below the first looper shaft having a plurality of arms thereon, the outer ends of which are provided with hooks for entering the loops and transferring them from the first hooks on the first looper shaft and moving the loops further downwardly to further elongate the same, a third oscillatable shaft disposed below and rearwardly of the second oscillatable shaft and having a plurality of looper bills mounted thereon, the looper bills being adapted to pass into the loops while they are held by the hooks on the second looper members and to hold the loops while the second loopers move out of the same, and a fourth oscillatable shaft having a plurality of cutter members thereon adapted to rub against the looper bills and cut some but not all of the loops held on the looper bills during

oscillation of the looper bills rearwardly with relation to the first and second looper shafts.

4. In a sewing machine having a vertically reciprocating needle for carrying a strand through a fabric, means for passing between the strand and the needle for forming a loop and for moving the loop downwardly to elongated position while the needle moves upwardly, a second means for passing into the loop while it is held in lowered position by the first means and moving the loop further downwardly to further elongate the same, and third means for entering the loop while it is held by the second means for transferring the loop from second means to the third means.

JOSEPH K. McCUTCHEON.
